12 Claims. (Cl. 315—218)

1

This invention relates to ignition systems which employ magnetogenerators as the source of electrical power, and more particularly to voltage doubler ignition systems of the type described and claimed in U. S. Patent 2,456,475 to Wargin et al., dated December 14, 1948.

In ignition systems which utilize two voltage impulses in connection with a voltage doubler circuit to fire a single spark plug, the timing of the voltage impulses is very important. This is particularly true in cases, such as in aircraft engines, where it is necessary to operate a large number of spark plugs from a single distributor. In such cases the space between distributor electrodes and the time between spark plug discharges are both limited, making it difficult to insure that two complete charges are generated before the time for discharge. It is an object of this invention to provide an ignition system which insures that two complete charges are generated before the time for discharge is reached.

It is a further object of the present invention to provide an ignition system which utilizes irregularly occurring voltage impulses.

In carrying out our invention in one form, we provide an alternating polarity magnetogenerator of the inductor type having teeth on alternate stator poles of unequal width. Such a magnetogenerator is claimed in our copending application Serial No. 120,752, filed October 11, 1949, now Patent 2,553,298, issued May 15, 1951, of which the present application is a division.

The unbalanced alternating flux produced by the rotation of the rotor of such a magnetogenerator results in alternating voltage impulses in the voltage output coils of the magneto separated by different time intervals for one polarity than for the other. This alternating voltage is applied to a voltage doubler circuit in a breakerless type ignition system providing for low tension distribution. The voltage doubler circuit, in turn, impresses the aggregate of two complete charges for each spark plug operation on transformer type spark plugs through an air-gap type distributor. The use in our ignition system of voltage impulses which occur at irregular intervals insures that two complete charges are generated before each spark plug discharge because it is possible with such an arrangement to generate two complete charges in a shorter interval than would otherwise be the case.

For a clearer and more complete understanding of our invention, reference should be had to the accompanying drawing in which Fig. 1 is a schematic diagram of a preferred embodiment of the invention; Fig. 2 is a partial schematic diagram illustrating the magnetogenerator in a different rotational position than Fig. 1; while in Figs. 3A, 3B and 3C there are shown curves to facilitate the understanding of the invention.

2

Referring to Fig. 1 of the drawing, there is shown a breakerless ignition system of the low tension high frequency type for which electrical power is supplied by a magnetogenerator indicated generally at 1. The magnetogenerator illustrated is of the inductor type and comprises a rotary member 2 mounted on a drive shaft 3, which may be driven by any suitable means (not shown). The rotor 2 is formed of magnetic material and is preferably of laminated construction, the rotor being provided with a plurality of circumferentially spaced teeth 4. Extending around the rotor member 2 is a stator member comprising four spaced arcuate pole pieces 5, 6, 7 and 8. Stator pole pieces 5 and 7 are provided with a plurality of inwardly extending projections or teeth 9, while pole pieces 6 and 8 are provided with a plurality of inwardly extending teeth 10. The stator teeth 9 and 10 cooperate with the rotor teeth 4 in establishing different low reluctance magnetic circuit paths through the rotor and the stator pole pieces as is subsequently described in detail.

The magnetogenerator 1 is provided with two output coils 11 and 12 which are mounted, respectively, on magnetic core members 13 and 14. As illustrated in the drawing, the core member 13 is arranged magnetically to interconnect the stator pole pieces 5 and 6, while core member 14 is arranged magnetically to interconnect stator pole pieces 7 and 8, the core members 13 and 14 being located on diametrically opposite sides of the stator.

For the purpose of providing a source of magnetic flux which is periodically directed through the core members 13 and 14 in opposite directions upon the rotation of the member 2, there are provided two permanent magnets 15 and 16 located on diametrically opposite sides of the stator. As shown, the permanent magnet 15 is arranged so that its polar extremities abut the adjacent ends of pole pieces 6 and 7 and thereby forms a magnetic link between these two pole pieces. The permanent magnet 16 is similarly arranged with its polar extremities abutting the adjacent ends of pole pieces 5 and 8, and acting as a magnetic link interconnecting these two pole pieces.

When the rotor 2 of the magneto rotates, the magnetic flux of the permanent magnets 15 and 16 is caused first to pass through the core members 13 and 14 in one direction and then to be rapidly changed or switched so as to flow through the core members in the reverse direction, this alternate and rapid flux switching causing high induced voltages in the magneto output coils 11 and 12. This flux switching action of the magnetogenerator may be more easily understood by consideration of the low reluctance magnetic flux paths when the generator rotor is in each of

the two different positions illustrated, respectively, in Figs. 1 and 2 of the drawing. When the rotor is in the position shown in Fig. 1 of the drawing, the rotor teeth 4 lie opposite the stator teeth 10 on pole pieces 6 and 8, whereby a low reluctance path is established interconnecting these two pole pieces diametrically across the rotor. At this time the teeth 9 of pole pieces 5 and 7 are out of registration with the rotor teeth so that the flux path between these two pole pieces extending diametrically across the rotor is of relatively high reluctance. With the rotor of the generator in the position shown in Fig. 1, two low reluctance magnetic circuit paths are established, one of which may be traced as follows: The north pole of magnet 16, stator pole piece 5, core member 13, stator pole piece 6, diametrically across rotor member 2, stator pole piece 8 and back to the south pole of permanent magnet 16. The other of these two paths may be traced from the north pole of magnet 15 through stator pole piece 6 diametrically across rotor member 2, through stator pole piece 8, core member 14, stator pole piece 7 and back to the south pole of magnet 15.

When the rotor member 2 of the magneto-generator rotates counter-clockwise an amount approximately equal to one-half the pitch of the rotor teeth, it occupies the position shown in Fig. 2 of the drawing. Referring to this figure, it will be seen that the rotor member 2 now establishes a low reluctance magnetic circuit path extending diametrically across rotor 2 between pole pieces 5 and 7. At this time, rotor teeth 4 are out of registration with teeth 10 on stator pole pieces 6 and 8 so that the reluctance of the magnetic circuit path extending diametrically across the rotor between pole pieces 6 and 8 is relatively high. With the rotor in the position shown in Fig. 2, it will be noted that there are now two low reluctance magnetic paths whereby the magnetic flux of permanent magnets 15 and 16 threads the core members 13 and 14 in the opposite direction from that shown in Fig. 1. One of these paths may be traced as follows: The north pole of permanent magnet 15, stator pole piece 6, core member 13, stator pole piece 5, diametrically across rotor 2, stator pole piece 7 and back to the south pole of permanent magnet 15.

It will be noted from Figs. 1 and 2 that teeth 9 on stator pole pieces 5 and 7 are of greater width and, hence, of greater lateral cross-section than teeth 10 on pole pieces 6 and 8, although all stator teeth are made relatively narrow for reasons which are given subsequently. The effect of the difference in lateral dimensions of stator teeth 9 and 10 is to cause the magnetic flux through core members 13 and 14 to reverse at irregular intervals. This is due to the fact that rotor teeth 4 are opposite the wider stator teeth 9 in flux conducting relationship therewith for a greater interval than for the narrower teeth 10, the radial air gap between rotor teeth 4 and the stator teeth being substantially the same in both cases. These irregularly spaced flux reversals produce alternating voltages in coils 11 and 12 having a different interval for one polarity than for the other, and these are used to advantage in our improved ignition system, as is explained below.

In order that the voltages induced in coils 11 and 12 may be as high as possible, the magneto rotor and stator teeth are so designed as to cause a very rapid change in the magnetic flux threading core members 13 and 14 while the rotor mem-

ber 2 is rotating. In order to accomplish this, the stator teeth 9 and 10 are formed so that their width is relatively small. In many cases, these teeth are made as narrow as possible consistent with rigid construction and good manufacturing practices. In most cases, the stator teeth are appreciably narrower than the rotor teeth 4, although this may not be the case in a relatively high speed magneto. While the expedient of making a single stator tooth narrow is desirable from the standpoint of obtaining a rapid flux change, it has the disadvantage that it reduces the longitudinal cross-sectional area of the stator tooth for an axial tooth length of any given value. The amount of magnetic energy required to be stored in the magnetic circuit of the magneto for each impulse determines the longitudinal cross-sectional area of the stator teeth and, therefore, in the conventional single-tooth stator construction this results in unduly long stator teeth, which is undesirable from the size standpoint. In the present arrangement, this difficulty is obviated by using a plurality of parallel stator teeth on each pole piece so as to provide a plurality of parallel flux paths across the air gap to the rotor. Thus, it will be noted that each of the stator pole pieces 5, 6, 7 and 8 is provided with three inwardly extending teeth. This arrangement permits the necessary amount of pole piece cross-sectional area to conduct the required amount of flux without necessitating undesirably long stator teeth. Obviously, more or less than three stator teeth per pole can be used, depending upon the number of rotor teeth being used and the amount of flux which is required in a particular case.

Referring now to the details of the ignition distribution arrangement, and more particularly to the distribution arrangement associated with magneto output coil 11, it will be noted that there is provided a pair of series connected storage condensers 17 and 18 having a common terminal 19 which is connected to one of the output leads 20 of the coil 11. The remaining terminal 25 of the condenser 17 is connected to the other coil lead 21 through a half-wave rectifier 22. The remaining terminal 23 of the condenser 18 is also connected to the coil lead 21 through a parallel circuit, including another half-wave rectifier 24. The magnetic and electrical polarities are so selected in connection with the current conducting directions of rectifiers 22 and 24 that when the output of coil 11 is of one polarity, one of the condensers, say condenser 17, is charged. Due to the action of rectifiers 22 and 24, the next succeeding voltage impulse of opposite polarity of coil 11 causes the condenser 18 to be charged while the charge on condenser 17 is maintained. The polarities of the condensers 17 and 18 when charged are such that they are series aiding or additive, that is, the voltage across terminals 21 and 23, when the condensers are fully charged, is substantially greater than across either condenser alone, and may be approximately twice as great for the illustrated case where two condensers were used.

In order to utilize this cascading arrangement advantageously, a circuit arrangement is provided whereby the voltage across the terminals 21 and 23 is periodically supplied by a distributor to various ignition circuits to fire spark plugs associated therewith. To this end, the terminal 25 is grounded, as indicated, and the terminal 23 is connected through a lead 26 to a rotary distributor, indicated generally at 27. The distributor 27 is shown as comprising a plurality of station-

ary electrodes 28 which are arranged in a circular pattern. Cooperating with the stationary electrodes 28 is a rotary electrode or a distributor finger 29, which may be conveniently mounted on shaft 3, as shown, so as to be rotated in synchronism with the rotor member 2 of the magnetogenerator. The lead 26 is connected to distributor finger 29 through a slip ring arrangement 30 of conventional construction.

The ignition circuits illustrated are of the so-called low tension high frequency type. For the purpose of simplicity, only one such circuit is illustrated in Fig. 1 for distributor 27, but it will be understood that in actual practice there is a separate ignition circuit and associated spark plug connected to each of the stationary distributor electrodes.

The ignition circuit shown in connection with the distributor 27 comprises a step-up transformer 31 having a primary or low voltage winding 32 and a secondary or high voltage winding 33. The high voltage winding 33 is connected to energize a spark plug 34, while the primary winding 32 is arranged to be periodically connected by the distributor 27 to be energized by series-connected condensers 17 and 18. In ignition systems of this type, a spark gap is used to initiate a high frequency oscillatory discharge in the primary circuit of transformer 31 and in the illustrated arrangement the distributor used is of the air-gap type in which the required spark discharge takes place between the rotary distributor finger 29 and stationary electrodes 28. Thus, as distributor finger 29 rotates, it approaches to within arcing distance of the electrodes 28, but does not actually come in contact with them. An advantage of this type of ignition circuit lies in the fact that the distributor voltage may be of relatively low magnitude, for example, on the order of three kilovolts, while the high voltage applied to the spark plugs, which may, for example, be of the order of 18 kilovolts, is confined to the spark plug and the secondary winding of the step-up transformer. In order to eliminate corona loss to the surrounding atmosphere, step-up transformer 31 may be advantageously hermetically sealed in the spark plug, as will be well understood by those skilled in the art.

In ignition systems for radial engines, there must be provided compensation for timing irregularities which occur because of the use of articulated piston rods. In conventional ignition systems of the breaker type, this compensation is usually provided by properly selecting the angular relation of the cam lobes used to operate the breaker switch. In the present breakerless system, some other method must be used. Such timing compensation can be conveniently obtained in the present system by an appropriate circumferential spacing of the stationary distributor electrodes.

One of the principal advantages of this invention is that it permits such compensation, by means of angular adjustment of the stationary distributor electrodes, without detrimental effect on the operation of the ignition system. This will be more readily understood by reference to the curves of Figs. 3A, 3B, and 3C of the drawing. In Fig. 3A is shown a typical voltage wave resulting from a double voltage impulse from a magnetogenerator having voltage impulses occurring at regular intervals. In Fig. 3B is shown a typical voltage wave of an ignition system employing the present invention. It will be noted from the curve of Fig. 3B that the voltage rises to the peak

5 voltage required to completely charge the condensers earlier in the cycle than with the conventional generator and thereby allows an ample compensation and firing interval. In Fig. 3C, is shown the magnetogenerator flux wave corresponding to the output voltage wave of Fig. 3B.

6 The construction of the magnetogenerator 1 is such that it lends itself advantageously to the dual ignition arrangement illustrated in Fig. 1, wherein separate distribution circuits are associated with each of the two output coils 11 and 12, the distribution circuit associated with coil 11 having been described above. In order to utilize advantageously the output of the second magnetocoil 12, there is provided another ignition distribution system which may be, as shown, the same as the corresponding parts of the previous distribution system already described in connection with coil 11. Parts of the second distribution system corresponding to those already described have been given corresponding reference numerals, except that the numerals have been primed in order to differentiate between the systems.

25 In order to clarify the description of operation of our improved ignition system by a concrete example, there is illustrated in Fig. 1 a system which provides dual ignition for an internal combustion engine having 14 cylinders. In the system illustrated, the rotor 2 of the magnetogenerator is provided with 14 teeth and each of the distributors is provided with 14 stationary electrodes, making a total of 28 electrodes which are connected to 28 separate ignition circuits. With this arrangement, the shaft 3 which drives the magnetogenerator rotor and the distributor finger 29 and 29' may be connected to the internal combustion engine so as to operate at one-half engine crank-shaft speed. The characteristic of the magnetogenerator 1 is such that it inherently produces a number of impulses of alternating polarity in each of the coils 11 and 12 equal to twice the number of rotor teeth for each revolution of the rotor shaft. Thus, in the illustrated arrangement, there are 28 voltage impulses of alternate polarity induced in each of the coils 11 and 12 for each revolution of the drive shaft 3. Assuming the electrodes 28 and 28' to be equally spaced except for small angular irregularities to provide timing compensation, it will be clear from Fig. 3B that the magnetogenerator 1 produces two complete voltage impulses in the time interval required for each distributor finger to move from a position opposite one electrode to a position opposite the next adjacent electrode. Thus, the series-connected storage condensers are fully charged and ready for discharge through an ignition circuit each time a distributor finger moves opposite a stationary electrode. With this arrangement, it will be clear that the 28 ignition circuits are periodically and sequentially fired in pairs so that the system can be utilized to provide dual ignition for an engine having 14 cylinders.

65 It will also be readily understood by those skilled in the art that the system illustrated in Figs. 1 and 2 may be used to provide dual ignition for engines having an odd or even number of cylinders by providing a suitable number of teeth on the magnetorotor and suitable quantities of stationary electrodes for the distributors. Also, by utilizing only one of the output coils, provision may be made for single ignition for an odd or even number of cylinders. Similarly, provision may be made for more than two voltage impulses 70 per firing interval, if desired.

While we have shown a particular magneto-generator for use in our improved breakerless ignition system, it should be understood that our invention is not limited to the use of this specific generator. Any generator may be used which provides an alternating potential having a different interval for one polarity than the other.

In connection with the magnetogenerator illustrated it will be noted in Figs. 1 and 2 that the circumferential spacing between the adjacent endmost teeth 9 and 10 on adjacent stator pieces is equal to approximately one and a half times the tooth-pitch of the rotor teeth, the distance being measured between the center lines of the stator teeth. It will be understood that this spacing may be any odd multiple of one-half the pitch of the rotor teeth, that is, one-half, one and one-half, two and one-half, etc., as long as the rotor teeth 4 are out of register with stator teeth 10 when they are in register with stator teeth 9 and vice versa.

An important advantage of the present invention is that it results in a considerably wider band of no electrical activity, as shown in Figs. 3B and 3C, in which most values of distributor electrode compensation may be spanned without the spark discharge interrupting the voltage wave.

An additional advantage is that it stabilizes the level of the voltage to which the condensers are charged for each spark, since two complete voltage impulses are applied to the condensers for each spark.

By making all peak voltages uniform, this invention makes possible an increase in the altitude ceiling for ignition systems for aircraft engines, since there is no voltage higher than the desired minimum condenser charging voltage.

A still further advantage is that it reduces the amount of loss from the charge on the first condenser of a pair resulting from the first impulse, through the leakage of the rectifiers, because there is not as much time for decay before the second impulse occurs.

A still further advantage is that it makes more practical the use of a voltage multiplier electrical circuit in an ignition system, especially for use in engines of 14 or more cylinders in which the time for ignition of each spark plug and the angular spacing between distributor electrodes becomes critical.

While we have illustrated and described a preferred embodiment of our invention, modifications thereof may be made by those skilled in the art without departing from the spirit and scope of the invention. Therefore, it should be understood that we intend to cover by the appended claims all such modifications as fall within the spirit and scope of our invention.

What we claim as new and desire to secure by Letters Patent of the United States is:

1. In an ignition system, generator means for providing alternating polarity voltage impulses having a first interval for one polarity and a different interval for the other polarity, voltage doubler type circuit means including a plurality of condensers connected series aiding, whereby a voltage impulse from said generator means charges one of said condensers and a later voltage impulse from said generator means charges another of said condensers, and discharging means arranged to simultaneously discharge said series connected condensers through ignition apparatus.

2. An ignition system comprising generator

means for producing alternating polarity voltage impulses having a lesser time interval for impulses of one polarity than the other, a pair of condensers connected series aiding, circuit means including rectifiers for connecting said condensers to said generator means in a manner such that a voltage impulse of one polarity charges one of said condensers and a voltage impulse of the other polarity charges the other of said condensers, and a distributor arranged to simultaneously discharge said series connected condensers through ignition apparatus.

3. In combination, an alternating voltage generator having a greater interval for one polarity than the other, circuit means of the voltage doubling type coupled to said generator and receiving alternating voltage therefrom, said circuit means including condenser means charged to a direct voltage greater than the amplitude of said alternating voltage, and discharging circuit means for discharging said condenser means at periodic intervals at least as great as two half cycles of said alternating voltage.

4. An ignition system comprising generator means for producing alternating polarity voltage impulses having a lesser interval for one polarity than for the other polarity, a pair of condensers connected series aiding, circuit means including rectifiers for connecting said condensers to said generator means in a manner such that a voltage impulse of said one polarity charges one of said condensers and a voltage impulse of said other polarity charges the second of said condensers, and discharging means arranged to simultaneously discharge said series connected condensers during the latter portion of the interval for said other polarity.

5. An ignition system comprising generator means for producing alternating polarity voltage impulses, said means providing a predetermined time interval for one polarity and a greater interval for the other polarity, voltage doubler type circuit means including a pair of condensers connected series aiding, whereby a voltage impulse of said one polarity from said generator means charges one of said condensers and a later impulse of the other polarity from said generator means charges the other of said condensers, and periodic discharging means arranged to simultaneously discharge said series connected condensers through ignition apparatus during the latter portion of the interval for said other polarity.

6. In an ignition system, an alternating polarity generator for producing voltage impulses, said generator having a first predetermined interval for impulses of one polarity and a longer interval for impulses of the other polarity, a pair of condensers connected series aiding, circuit means including rectifiers interconnecting said condensers and said generator in a manner such that a voltage impulse from said generator of one polarity charges one of said condensers during said predetermined interval and a voltage impulse of the opposite polarity charges another of said condensers during said longer interval, means for connecting said condensers in series so that the charges thereon are additive, and a distributor arranged to simultaneously discharge said condensers during the latter portion of said longer interval, said generator and said distributor being synchronized and correlated so that each of said condensers receives a charging impulse from said generator prior to said discharge by said distributor.

7. An ignition system comprising a magneto having a rotatable member and an output coil which produces successive voltage impulses of different duration upon rotation of said rotatable member, a pair of condensers connected series aiding, selective charging circuit means connecting said condensers to said coil so that a voltage impulse followed by an interval of one duration charges a first one of said condensers and a subsequent impulse followed by an interval of longer duration charges the other of said condensers while the charge on said first condenser is maintained, and a distributor arranged to simultaneously discharge said series connected condensers through ignition apparatus, said rotatable member and said distributor being synchronized and correlated so that each of said condensers receives a charging impulse from said output coil prior to discharge through said distributor.

8. In an ignition system, a generator for producing voltage impulses of alternating polarity, said generator providing a greater interval for impulses of one polarity than the other polarity, a plurality of condensers connected series aiding, charging circuit means including rectifier means connected between said generator and said condensers for charging one of said condensers upon the production of a voltage impulse during the lesser interval and for charging another of said condensers upon the production of a voltage impulse during said greater interval, a distributor arranged to simultaneously discharge said series connected condensers, and synchronizing means for said generator and distributor, said last-mentioned means driving said distributor at a rate to discharge said condensers after each has received at least one charging impulse from said generator and before the termination of said greater interval.

9. An ignition system comprising a magneto having a rotatable member and an output coil which produces successive voltage impulses of alternating polarity upon rotation of said rotatable member, said magneto providing a greater interval for impulses of one polarity than the other polarity, a pair of condensers connected series aiding, circuit means including rectifiers for connecting said condensers to said coil so that a voltage impulse of one polarity charges one of said condensers and a voltage impulse of the opposite polarity charges the other of said condensers, and a distributor arranged to simultaneously discharge said series connected condensers through ignition apparatus, said rotatable member and said distributor being synchronized and correlated so that each of said condensers receives a charging impulse from said output coil prior to said discharge through said distributor.

10. An ignition system comprising a breakerless magneto of the inductor type having an output coil in which voltages of alternating polarity are induced, said magneto providing a greater interval for voltages of one polarity than the other polarity, a pair of series connected condensers, circuit means including rectifiers interconnecting said condensers and said output coil in such manner that consecutive output coil voltages of alternating polarity cause sequential charging of said condensers whereby the voltage across said series connected condensers when charged is greater than the voltage induced in said output coil during each voltage impulse thereof, and a rotary distributor mechanically synchronized with said generator arranged to periodically dis-

charge said series connected condensers after each of said condensers has received a charging impulse from said output coil.

11. An ignition system comprising an alternating polarity generator providing a lesser interval for one polarity than for the other polarity, a pair of condensers connected series aiding, charging circuit means including rectifier means connected between said generator and said condensers for charging one of said condensers upon the production of a voltage impulse during the lesser interval and for charging the other of said condensers upon the production of a voltage impulse during said greater interval, and an air-gap type distributor arranged to discharge simultaneously said series connected condensers, said distributor comprising a plurality of spaced stationary electrodes positioned in circular relation and a cooperating finger member connected to said condensers and rotatable successively adjacent said stationary electrodes in operative relation therewith, said distributor and said generator being synchronized whereby said condensers are discharged successively through said stationary electrodes during successive greater intervals.

12. An ignition system comprising a magneto having a rotatable member and two output coils in which successive voltage impulses are induced upon rotation of said rotatable member, said magneto providing a lesser time interval for impulses of one polarity than the other, a first circuit means of the voltage doubling type including a pair of condensers connected to one of said coils so as to be sequentially charged by successive voltage impulses from said one coil, the first of said pair of condensers being charged during said lesser interval and second during the greater interval, a second circuit means of the voltage doubling type including a pair of condensers connected to the other of said coils so as to be sequentially charged by successive voltage impulses from said other coil, the first of said second pair of condensers being charged during said lesser interval and the second during said greater interval, a pair of distributors each comprising a set of stationary electrodes and a cooperating rotatable finger member, means for rotating the finger members of said distributors and said magneto rotatable member at predetermined relative speeds, the spacing between successive electrodes of each of said distributors being such that two voltage impulses are induced in the associated magneto coil during the time interval required for a distributor finger to move from a position opposite one electrode to the position opposite an adjacent electrode, means for connecting each pair of condensers respectively to a rotating finger of one of said distributors, and an ignition circuit including a spark plug associated with each distributor stationary electrode, whereby all of the ignition circuits may be periodically energized by discharge from said condensers in sequence or two at a time depending upon whether said distributor fingers are initially set in staggered or synchronized relation.
